ELECTRICAL OUTLET

Burton B. Bierce, Pewaukee, Wis., assignor of
one-half to Elwin A. Andrus, Milwaukee, Wis.

Application July 1, 1946, Serial No. 680,601

5 Claims. (Cl. 173—330)

1

This invention relates to an electrical outlet of the general type employed for supplying current to various electrical devices wherein a two prong plug makes connection with the outlet.

One of the principal objects of the invention is to provide an outlet which is more safe from the meddling of children and possible injury to children and others by shocks.

Another object of the invention is to provide an outlet of standard size with a ground connection suitable for grounding electrical apparatus connected thereto, and which is safe against accidental shorting.

Another object is to provide such an outlet that is of simple durable construction and of low cost to manufacture.

Another object is to provide an outlet which will automatically prevent dirt and moisture from entering the slots for the connecting prongs.

Another object is to provide an outlet having a rotary cover plate and in which the plate is positively and automatically returned to a position where it covers the contact slots when the prongs of the plug are removed.

Another object is to provide such an outlet in which the prongs of the plug are in the same plane when initially inserted at the start of a plugging operation as they are at the final position of complete insertion into the outlet.

Other objects and advantages appear in the following description of an embodiment of the invention illustrated in the accompanying drawings.

In the drawings:

Figure 1 is a perspective view of a double outlet with one of the outlets exploded to show the parts prior to assembly;

Fig. 2 is a section through one of the assembled outlets taken on the longitudinal center line of the structure;

Fig. 3 is a section taken transversely of Fig. 2 across the outlet on line 3—3 of Fig. 2;

Fig. 4 is a section taken on line 4—4 of Fig. 2;

Fig. 5 is a face elevation of one of the outlets;

Fig. 6 is a perspective view of a plug having a third central prong for use with the outlet in grounding electrical apparatus; and

Fig. 7 is a section showing the plug inserted in the socket.

The plug constitutes the subject matter of a copending application Serial No. 680,600, now abandoned, filed on even date herewith by the present inventor.

The outlet is of standard size to fit into any regular outlet box and to receive any standard plug connection.

The outlet comprises a suitable porcelain, phenolic resin or similar set plastic insulating base 1 having a pair of upstanding circular body sections 2 on its front providing an outlet face at 60 each end of the base.

The back of the base 1 has a longitudinal

groove 3 in which lies a metal strip 4 extending longitudinally of the base and having its ends formed to provide flanges 5 that are adapted to be secured to the outlet box by suitable screws to hold the outlet in place.

The lead wires for current are connected by the corresponding screw posts 6 to opposite copper conductor strips 7 disposed along the opposite sides of the base.

10 The ends of strips 7 enter the corresponding body sections 2 and are formed to provide spring contacts 8 disposed in the corresponding slots 9 in the faces of the body sections.

15 Each body section 2 has its face recessed to receive an inner circular disc 10 and an outer circular disc 11 which serve to cover slots 9 when in normal position to prevent accidental shorting of the contacts 8.

20 Each disc 10 has a pair of slots 12, and each disc 11 has a pair of slots 13, corresponding to the slots 9 in the body section. Both discs are mounted for rotation in the body section and are held in place by a central rivet 14 which leaves the same free to turn thereon.

25 When in normal position, disc 10 is turned 90° from a position of registry of its slots 12 with the corresponding slots 9 of the body section, so that the disc completely covers slots 9.

When in normal position, disc 11 has its slots 30 13 in alignment with slots 9 of the body section.

The discs 10 and 11 are biased to normal position by a coil spring 15 preferably of the tension type lying in a circumferential recess 16 in the disc 10 and secured at one end to a projection

35 17 in the recess and at the other end to a pin 18 extending into the recess from disc 11.

40 The projection 17 is disposed about centrally of recess 16 and the spring 15 lies in one end of the recess defined by the projection and one end wall. The other end of recess 16 receives a stop 19 projecting from the side wall of the body section 2.

A groove 20 is cut along the inner corner edge of disc 11 to receive a part of stop 19.

45 The stop 19 limits the rotational movement of discs 10 and 11 and provides for a 90° separation of slots 12 and 13 under the biasing action of spring 15.

When it is desired to insert the prongs 21 of a standard plug 22 into slots 9 to make contact with contacts 8, the ends of the prongs 21 are first inserted in slots 13 into engagement with disc 10. The plug 22 and disc 11 are then turned to the right 90° until the prongs 21 register with 55 and enter slots 12 of disc 10. The plug 22 and discs 10 and 11 are then turned to the left 90° to the original plane of the prongs, and the latter are then pushed into slots 9 to complete the electrical connection.

The dual disc construction requiring turning in both directions in order to complete the connection provides a protection against the med-

dling of children which is not present with single discs. It provides an indication of the plane for the prongs of the plug, the outer slots 13 being preferably in alignment with slots 9.

The dual disc construction wherein the discs are biased relative to each other by spring 15 provides for a gripping of the prongs 21 when the connection is completed and thereby prevents accidental displacement of the plug and removal of the prongs. The contacts 8 are relieved of any stress from spring 15 since discs 10 and 11 are floating with respect to the body section 2.

When it is desired to remove the plug 22 it is merely pulled straight out, allowing spring 15 to bias disc 10 to the right 90° to close the slots 9 and 13. Stop 10 determines the final normal position for the discs 10 and 11.

The invention, as above described, provides a safety cover for the outlet contacts and prevents accidental shorting of the same.

Another phase of the invention, which has particular advantage when used with the safety cover, lies in a ground provided for electrical apparatus. For this purpose, the rivet 14 is secured through the back strip 4 and makes electrical contact therewith.

The front end of rivet 14 has a cylindrical recess 23 therein for receiving a central ground prong 24 of the plug. The wire 25 connecting the plug 22 with the electrical apparatus to be operated is preferably of the three wire type, one of the wires constituting a ground wire connected to the casing of the apparatus and to central prong 24.

The exposure of rivet 14 as a ground terminal is not dangerous, and its proximity to contacts 8 is also not dangerous so long as the latter are covered by disc 10.

This second phase of the invention provides a simple means for grounding electric motor appliances and electric shavers and the like. It provides greater safety in the operation of all electrical appliances.

The present invention is applicable to the construction of removable cover plate adapters for standard outlet sockets, as set forth and claimed in applicant's copending application Serial No. 688,324, now Patent No. 2,524,250, filed August 3, 1946, and which constitutes a continuation in part hereof.

The invention may have various embodiments within the scope of the accompanying claims.

I claim:

1. An electrical outlet comprising a body having a generally circular face with a pair of spaced slots with electrical contacts disposed therein, a pair of generally circular discs rotatably mounted on the face of said body and each disc having a pair of slots therethrough corresponding to the slots in said body, and means normally biasing said discs rotationally relative to each other to a position in which the corresponding slots of the discs are out of registry with each other and the slots of the inner disc are out of registry with the slots in said body to provide a cover for said contacts.

2. An electrical outlet comprising a body having a generally circular face with a pair of spaced slots with electrical contacts disposed therein, a pair of generally circular discs rotatably mounted on the face of said body and each disc having a pair of slots therethrough corresponding to the slots in said body, means normally biasing said discs rotationally relative to each other to a position in which the correspond-

ing slots of the discs are out of registry with each other, and means interlocking said discs and body rotationally to provide for a normal offsetting of the slots in the inner disc relative to the slots in the body.

3. An electrical outlet comprising a body having a generally circular face with a pair of spaced slots with electrical contacts disposed therein, a pair of generally circular discs rotatably mounted on the face of said body and each disc having a pair of slots therethrough corresponding to the slots in said body, means normally biasing said discs rotationally relative to each other to a position in which the corresponding slots of the discs are out of registry with each other, and means interlocking said discs and body rotationally to provide for a normal offsetting of the slots in the inner disc relative to the slots in the body and for the slots in the outer disc being normally disposed in alignment with those of the body.

4. An electrical outlet comprising a body having a generally circular face with a pair of spaced slots with electrical contacts disposed therein, a pair of generally circular discs rotatably mounted on the face of said body and each disc having a pair of slots therethrough corresponding to the slots in said body, means normally biasing said discs rotationally relative to each other to a position in which the corresponding slots of the discs are out of registry with each other and the slots of the inner disc are out of registry with the slots in said body to provide a cover for said contacts, and a ground connection constituting a central pin intermediate said slots and upon which said discs are rotatably mounted and which has a recess centrally thereof to receive a ground prong of a connecting plug.

5. An electrical outlet comprising a body having a generally circular face with a pair of spaced slots with electrical contacts disposed therein, a pair of generally circular discs rotatably mounted on the face of said body and each disc having a pair of slots therethrough corresponding to the slots in said body, means normally biasing said discs rotationally relative to each other to a position in which the corresponding slots of the discs are out of registry with each other, means interlocking said discs and body rotationally to provide for a normal offsetting of the slots in the inner disc relative to the slots in the body and for the slots in the outer disc being normally disposed in alignment with those of the body, and a ground connection constituting a central pin intermediate said slots and upon which said discs are rotatably mounted and which has a recess centrally thereof to receive a ground prong of a connecting plug.
